GAME BOARD

Vivian H. Hudson, Everett, Wash.

Application June 28, 1956, Serial No. 42,069

Term of patent 7 years

(Cl. D34—5)

FIG. 1

The essential features of my design reside in the portions shown in solid lines on the drawing.

I claim:

The ornamental design for a game board, substantially as shown and described.
